UNITED STATES PATENT OFFICE.

ARTHUR J. RAY, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed June 23, 1924. Serial No. 721,615.

The present invention relates in general to telephone systems, but is concerned more particularly with non-numerical trunking arrangements as applied to telephone systems.

5 The main object of the invention is the provision of new and improved circuit arrangements for distributing the traffic amongst the various trunks accessible to a group of non-numerical switches of the type 10 that have no normal position, in order that two successive calls handled by the same non-numerical switch do not take the same trunk. This avoids the possibility of a defective trunk being used repeatedly by the same non- 15 numerical switch with the result that all calls coming into such non-numerical switch during this period are lost on account of the defective trunk.

The applicant is aware of the fact that the 20 foregoing is not broadly new, arrangements being known in which a non-numerical switch is automatically advanced one or more steps upon the release of a connection. This arrangement, however, while in most cases 25 satisfactory from an operating standpoint, is in many cases very difficult to carry out on account of the somewhat complicated circuit arrangement required. It is, therefore, 30 one object of the invention to provide new and improved circuit arrangements whereby a non-numerical switch is advanced one or more steps automatically upon being taken for use, rather than upon being freed. Other 35 objects have to do with the necessary circuit details as will appear hereinafter.

Referring now to the accompanying drawings comprising Figs. 1, 2, and 3, they show by means of the usual circuit diagrams, a sufficient amount of apparatus involved in a 40 telephone system embodying the principles of the invention, to enable the invention to be understood and its utility appreciated.

Fig. 1 shows the line switch LS individual to the line of substation A and having access to the selector S; Fig. 2 shows the secondary line switch SLS, which is accessible to the selector S, Fig. 1, and which has access to the repeater R which is associated with a trunk outgoing to a distant office; and Fig. 3 shows a desirable modification of the secondary line switch SLS, Fig. 2.

Regarding the equipment shown, the substation A is an ordinary automatic substation of the two-wire type and has the usual 55 talking and signalling instrumentalities, as

well as a calling device for controlling the automatic switches; the line switch LS is mechanically of the well known rotary type in which the wipers have no normal position and are advanced in a forward direction only, 60 being advanced upon the backward stroke of the associated stepping magnet, rather than upon the forward stroke, and has suitable circuit arrangements for causing it to advance (when it is seized) from the trunk 65 last used, even though such trunk may be idle; the selector S is a two-wire selector from a circuit standpoint and from a mechanical standpoint is of the well known vertical and rotary type, having bank contacts 70 which are arranged in horizontal rows or levels; the secondary line switch SLS is provided for the purpose of increasing the efficiency of the trunks in the associated outgoing group and, aside from its somewhat 75 different circuit arrangements necessitated by the different condition under which it operates, is similar to the line switch LS mechanically and also in that it is always advanced automatically when seized; and the repeater R is an ordinary two-wire repeater and is provided primarily in order to permit the use of a two conductor inter-office trunk, and it accordingly supplies ground, when seized, to the associated release trunk conductor to hold up the connection. 80

The detailed description of the operation of the apparatus shown will now be given. For this purpose, it will be assumed that the subscriber at substation A, desiring to make a 90 call, removes his receiver. When the receiver is removed at substation A, line relay 13 of the line switch LS energizes over conductors 11 and 12 and closes at armature 16 a circuit for the slow-to-pull up relay 14, and at armature 17 closes a circuit for stepping magnet 28 through the jumper 27. This circuit includes armature 19 of relay 14 and its resting contact, but relay 14 being slow-to-pull up, permits this circuit to remain closed long 95 enough for stepping magnet 28 to energize preparatory to advancing the wipers 29, 30, and 31.

After a slight interval, relay 14 energizes and opens the circuit of stepping magnet 28 105 at armature 19, whereupon stepping magnet 28 deenergizes and advances the associated wipers one step. Relay 14 also places ground on private normal conductor 35 at armature 19, thereby making the calling line busy in 110

the banks of the connector switches having access to it, and closing a circuit for switching relay 15 and stepping magnet 28 in series. At the same time, relay 14 connects test wiper 30 to the junction of switching relay 15 and stepping magnet 28. In case the trunk upon which the wipers of the line switch are standing is idle, however, this latter operation is of no particular utility at this time, and switching relay 15, not being short circuited, energizes, seizing the trunk.

On the other hand, assuming the trunk to be busy, switching relay 15 is short circuited by the ground potential encountered upon the busy test contact by test wiper 30 and does not energize, and, stepping magnet 28 is energized from this same ground potential and, being self-interrupting, operates the wipers 29, 30, and 31 step by step in search of an idle trunk. When an idle trunk is reached, for example, the trunk comprising conductors 32-34, inclusive, switching relay 15, being no longer short circuited, energizes in series with stepping magnet 28. Stepping magnet 28, however, does not energize at this time on account of the high resistance of switching relay 15. Upon energizing, switching relay 15 closes a locking circuit for itself through the resistance 36 at armature 22, at the same time, opening its initial circuit through stepping magnet 28; opens the test circuit and prepares the holding circuit at armature 21; and at armatures 20 and 23 disconnects conductors 11 and 12 from the winding of line relay 13 and ground and extends them by way of wipers 29 and 31, the bank contact with which they are now in engagement, conductors 32 and 34, and armatures 57 and 60 and their resting contacts to the upper and lower windings, respectively, of the double wound line relay 41 of the selector S.

Line relay 41 now energizes over the calling line, its upper winding being connected directly to battery and its lower winding being connected to ground through the left hand winding of the common dial tone transformer, and closes at armature 51 a circuit for release relay 42 which energizes and prepares the vertical magnet circuit at armature 53, at the same time places ground upon the release trunk conductor 33 at armature 52, thereby closing the usual holding circuit for switching relay 15 of the line switch LS before the slow acting line relay 13 and relay 14 have had time to deenergize.

The calling subscriber now hears the dial tone placed on his line through the common dial tone transformer and through the lower winding of line relay 41 and knows that he may now dial the first digit. When he does so, line relay 41 is deenergized a corresponding number of times. Upon each deenergization, line relay 41 closes at armature 51 a circuit through armature 53 and its working contact and series relay 43 for vertical mag-

net 48. By the operation of vertical magnet 48, the wipers 51-53, inclusive, of the selector S are raised step by step and come to rest opposite the desired level of bank contacts. Relay 43 is energized in series with vertical magnet 48 and, being slow acting, maintains its armature attracted throughout the vertical movement. At armature 54, relay 43 closes, in conjunction with the off normal contacts 49 which close upon the first vertical step, a circuit through the interrupter contacts 50 for stepping relay 44 which thereupon energizes and closes a locking circuit for itself at armature 55, and at armature 56 prepares a circuit for the rotary magnet 48.

At the end of the vertical movement, the slow acting series relay 43 deenergizes and closes a circuit for the rotary magnet 48 at armature 54, whereupon rotary magnet 48 energizes and advances the wipers 61-63, inclusive, into engagement with the first set of bank contacts in the selected level, and, near the end of its stroke, opens the circuit of stepping relay 44 at the interrupter contacts 50. Stepping relay 44 now deenergizes and opens the circuit of rotary magnet 48 at armature 56, whereupon rotary magnet 48 deenergizes also and again closes its interrupter contacts. From this point, the operation depends upon whether the trunk terminating in the first set of bank contacts is busy or idle. If it is idle, switching relay 45 energizes and seizes it. On the other hand, if the trunk is busy, switching relay 45 is short circuited by the ground potential encountered on the busy test contact by test wiper 62 and does not energize, and stepping relay 44 is energized through test wiper 62 and closes at armature 56 a circuit for rotary magnet 48 which again energizes and advances the wipers 61-63, inclusive, another step. This alternate operation of stepping relay 44 and rotary magnet 48 continues as described until an idle trunk is reached, for example, the trunk comprising conductors 64-66, inclusive. When this occurs, switching relay 45, being no longer short circuited, energizes in series with stepping relay 44 from the grounded release trunk conductor 33 and through the off normal contacts 49 and the interrupter contacts 50. Stepping relay 44, however, does not energize at this time on account of the relatively high resistance of switching relay 45. Upon energizing, switching relay 45 disconnects ground from armature 51 of line relay 41 at armature 59, so as to prevent the release of the selector after the connection has been switched through and after relays 41 and 42 deenergized. Incidentally, this operation opens the circuit of release relay 42 without waiting for line relay 41 to deenergize and open it at armature 51. As a further result of the energization of relay 45, it opens the test circuit and prepares the holding cir-

120
125
130

cuit at armature 58, thereby grounding release trunk conductor 65; and at armatures 57 and 60 disconnects conductors 32 and 34 from line relay 41 and extends them by way of wipers 61 and 63, conductors 64 and 66, and armatures 112 and 116 to the winding of line relay 101 of the secondary line switch SLS and ground, respectively. This results in a circuit being closed for the slow-to-pull 5 up line relay 101 over the calling subscriber's line. This relay does not pull up instantly upon its circuit being closed but hesitates just a trifle, so as to give time for stepping magnet 103 to energize responsive 10 to the release trunk conductor 65 being grounded by the selector S as pointed out above. The circuit of stepping magnet 103 at this time includes the normally closed contacts controlled by armature 113, armature 109 and its resting contact, terminal 105, jumper 108, and the terminal 107, as well as the common conductor 125 which is connected to battery at armature 124 of the common relay 123. Upon energizing, stepping magnet 15 20 25 103 makes ready to operate the wipers 117-119, inclusive, when it subsequently deenergizes.

Upon energizing over the subscriber's line, line relay 101 opens the circuit of stepping magnet 103 at armature 109, whereupon stepping magnet 103 deenergizes and advances the associated wipers one step. Line relay 101 also places ground on release trunk conductor 65 at armature 109 through the normally closed contacts controlled by armature 113, thereby closing the usual holding circuit for the switching relays of the line switch LS and the selector S before the slow acting release relay 42 of the selector S has had time 40 to deenergize.

In the secondary line switch SLS, as a further result of the energization of line relay 101, it closes at armature 111 a circuit for switching 102 and stepping magnet 103 in series, and at armature 110 connects test wiper 118 to the junction of switching relay 102 and stepping magnet 103. Accordingly, the secondary line switch SLS selects an idle trunk in the same manner described for the primary line switch LS, which trunk, it may be assumed, is the one comprising conductors 120-122, inclusive. When this idle trunk is selected, switching relay 102 energizes in series with stepping magnet 103; opens the 45 test circuit and prepares the holding circuit at armature 114; switches the release trunk conductor 65 through to the test wiper 118 at armature 113 so as to establish a through holding circuit, at the same time opening a further point in the initial circuit over which the stepping magnet 103 was operated upon the seizure of the switch; closes a local locking circuit for itself through the resistance 50 55 60 65 104 at armature 115, at the same time disconnecting its lower winding terminal from the

stepping magnet 103; and at armatures 112 and 116 disconnects conductors 64 and 66 from the winding of line relay 101 and ground and extends them by way of wipers 117 and 119, the bank contacts with which 70 these wipers are in engagement, conductors 120 and 122, and the upper and lower left hand windings of the repeating coil of the repeater R to the line relay 141. Line relay 141 now energizes over the calling line and 75 closes at armature 143 a circuit for release relay 142. Release relay 142 now energizes and places ground upon release trunk conductor 121 at armature 145, thereby establishing the usual holding circuit before the slow 80 acting line relay 101 of the secondary line switch SLS has had time to deenergize.

As a further result of the energization of line relay 141 of the repeater R, it closes at armature 144 a bridge across the associated 85 trunk conductors 147 and 148 which are assumed to extend to and terminate in an incoming selector in a distant office. Accordingly, the said incoming selector is prepared for operation in the usual manner. 90

The calling subscriber may now complete the remaining part of the connection in any well known manner, and, when he replaces his receiver at the termination of the ensuing conversation, line relay 141 deenergizes and 95 opens the bridge across conductors 147 and 148 at armature 144 so as to release the switches in the distant office. At armature 143, relay 141 opens the circuit of release relay 142. Release relay 142 deenergizes after 100 an interval and removes ground from release trunk conductor 121 at armature 145, whereupon switching relay 102 of the secondary line switch SLS, switching relay 45 of the selector S, and switching relay 15 of the line 105 switch LS deenergize. Responsive to the deenergization of switching relay 45 of the selector S, release magnet 46 energizes over the following circuit: From ground by way of armature 59 and its resting contact, armature 110 51 and its resting contact, armature 53 and its resting contact, off normal spring 47 and its upper contact, and release magnet 46 to battery. Upon energizing, release magnet 46 restores the selector S to normal position 115 in the usual manner, whereupon its circuit is opened at off normal spring 47.

It has been pointed out in the foregoing how the line switch LS is caused to take one step automatically when the receiver is removed at substation A, whether the wipers of the line switch are standing upon an idle trunk or not. It will be appreciated that, with this arrangement, the subscriber at substation A will not be prevented, by a single 120 defective first selector from establishing a connection as might well occur if the line switch LS always took the same trunk for each call as long as that trunk remained idle. 125

It has been shown how this same feature 130

has been applied to the secondary line switch SLS so that in case the said secondary line switch SLS is used by the same subscriber for successive calls, a different outgoing trunk 5 will be taken in each case. This arrangement, in connection with the secondary line switch SLS, has a still further utility in case the secondary line switch happens to be first choice in the bank of a group of selectors, in 10 which case, a large percentage of calls might be lost due to the secondary line switch standing on a defective trunk during the time when the traffic is comparatively light.

Referring now to the line switch LS, Fig. 1, it will be remembered that this line switch is advanced one step automatically before its advance is placed under the control of the test wiper 30. In certain cases it may be desired to arrange the line switch LS so that it will 15 take two or more steps before its advance is placed under the control of its test wiper. When this arrangement is desired, the jumper 27 between the terminals 25 and 26 is omitted and a jumper is connected instead between 20 the terminals 24 and 26, with the result that when conductor 37 is grounded at armature 17 of line relay 13, a circuit is closed for stepping magnet 28 which includes the self-interrupting contacts thereof. Accordingly, 25 stepping magnet 28 operates in a buzzer-like manner until its circuit is opened at armature 19 upon the energization of the slow-to-pull up relay 14. The number of steps which is desired for the stepping magnet 28 to take is 30 independent of the regular testing operation may be regulated by the amount of slowness imparted to the relay 14 by adjustment in the ordinary manner. In this way, by adjusting the relays such as 14 with varying degrees of 35 stiffness, the condition may be obtained wherein certain of the line switches advance only one or two steps prior to the regular testing operation, while others advance three, four, or more steps prior to the regular testing operation, thus resulting in a more general mixup of the traffic and a more even distribution of the load amongst the various 40 trunks concerned.

This extra advantage however must be 45 weighed against the increased wear and tear on the switching mechanisms.

Somewhat similarly, the secondary line switch SLS may be arranged to take two or 50 more steps prior to the regular testing operation, as against one step, by omitting the jumper 108 which is connected between the terminals 105 and 107 and placing a jumper 55 between the terminals 105 and 106. The variable operation on the part of the secondary line switches, such as SLS, is obtained with 60 the jumper in the alternate position above pointed out by merely adjusting the line relays such as 101 all alike as the amount of time required for any one relay to pull up 65 subsequent to the seizure of the switch is con-

trolled by the length of the instant calling line.

Referring now again to the line switch LS, Fig. 1, it will be noted that battery is supplied to stepping magnet 28 over the common conductor 67, which is normally connected to battery through the working contact and armature 70 of the normally energized relay 69. This relay 69 is normally maintained energized over the conductor 68 which is common to the group of selectors 70 accessible to the line switch LS. For example, the particular branch of the common conductor 68 which extends to the selector S is normally grounded through armature 59 and its resting contact, armature 51 and its resting contact, armature 53 and its resting contact, and the off normal contacts 47. It will be appreciated, however, that as soon as the selector S is taken for use, the line and release relays 41 and 42 energize and the ground is removed at that point from the common conductor 68 and is maintained disconnected from conductor 68 by off normal spring 47, 80 which shifts to its alternate position upon the first vertical step of the shaft, until the selector S is finally restored to its normal position again. Therefore, when the last selector in the group becomes busy, the common conductor 68 is ungrounded at all points 85 and the all-trunks-busy relay 69 deenergizes and removes battery from the common stepping magnet supply conductor 67 so as to prevent the needless operation of the stepping magnets in case any other subscribers 90 remove their receivers during the time when relay 69 is deenergized. The calling subscribers who are thus unable to obtain connection with first selectors are informed of 95 this fact by the absence of the dial tone. 100

When a first selector becomes idle, ground is replaced on conductor 68, whereupon relay 69 energizes again and places battery on conductor 67 to permit the stepping magnets, such as the stepping magnet 28 of the 105 line switch LS, to operate.

It may be well to point out at this time that, although the switching relay 15 is initially energized in series with stepping magnet 28 and would ordinarily be deenergized 110 responsive to the removal of battery from stepping magnet 28, the circuit arrangement in this case is such that the switching relay 15 remains locked up through the resistance 36 and does not deenergize as when battery 115 is removed from the stepping magnet 28 by the common relay 69.

Referring now to Fig. 2, it may perhaps be 120 advisable to explain certain arrangements hitherto not discussed. It is to be understood that the secondary line switch SLS is only one line switch of a single sub-group and that a number of sub-groups, say ten, taken together constitute the main group of secondary line switches accessible on one level of 125 130

the first selectors. Assuming that there are ten sub-groups of secondary line switches, each of the ten trunks on the level shown of the selector S extends to a secondary line switch in a different sub-group. This arrangement, as is well known, is provided so that, as one or more of the sub-groups become busy during a time of heavy traffic, no calls need be lost but are instead diverted to 5 the sub-groups, which, as yet, contain idle secondary line switches. A secondary trunking system of the foregoing type, but employing only two sub-groups, is shown in Fig. 1, of the U. S. Patent 1,528,751, issued to Bellamy et al. March 10, 1925. When this arrangement is employed, it is necessary to provide means for rendering busy the remaining idle secondary line switches in a sub-group when all outgoing trunks accessible to such 10 sub-group of line switches are busy, so that no more calls come into this sub-group at such a time, but are diverted to the other sub-group as above mentioned. To this end, the common all-trunks-busy relay 123 has 15 been provided. Relay 123 is normally energized over the common conductor 126 which is grounded at each of the idle repeaters accessible to the secondary line switch SLS. For example, it is grounded at the repeater 20 R at armature 146 of release relay 142. Relay 123, as has been pointed out hereinbefore, maintains battery connected to the common conductor 125 at armature 124 to supply battery to the stepping magnets of all the 25 secondary line switches in the sub-group.

When the last trunk accessible to the secondary line switch SLS becomes busy, ground is removed at all points from conductor 126 and relay 123 deenergizes and shifts the common conductor 125 from battery to ground. This immediately stops the rotation of any 30 secondary switch in the sub-group that may happen to be searching for a trunk at this time, and it connects ground to the release 35 trunk conductors of all the remaining idle secondary switches. For example, if the secondary line switch SLS is at this time idle, release trunk conductor 65 is grounded over the following circuit: From ground by way 40 of the resting contact and armature 124 of the all-trunk busy relay 123, conductor 125, stepping magnet 103, jumper 108, resting contact and armature 109, and the normally closed contacts controlled by armature 113. 45 From this point on, no more traffic is permitted to come into this sub-group of switches, but is diverted to the other sub-groups.

When one trunk accessible to the secondary 50 line switch SLS becomes idle, relay 123 energizes again and shifts conductor 125 from ground back to battery again, thereby rendering all idle switches in the sub-group 55 available for use again and furnishing battery to the stepping magnets of said switches.

It will be noted that, although the switching relay 102 of the secondary line switch SLS is initially energized in series with stepping magnet 103, it remains locked up through the resistance 104 and armature 115 70 and does not deenergize responsive to the removal of battery from stepping magnet 103.

Referring now particularly to Fig. 3, the secondary line switch SLS' shown therein is a modification of the secondary line switch 75 SLS, Fig. 2, and the main difference between the two circuits is that, whereas, switching relay 102 of the secondary line switch SLS is initially energized in series with stepping magnet 103 and later locks up over an independent circuit, the switching relay of the secondary line switch SLS' is initially energized over a circuit which is independent of of the associated stepping magnet, thereby obviating the necessity of providing an ar- 80 mature and contacts corresponding to armature 115 and its associated contacts of switching relay 102. On the other hand, however, it is necessary in the case of the secondary line switch SLS' to make arrangements for 85 connecting the test wiper to the junction of the switching relay and the associated resistance in addition to connecting it to the stepping magnet so as to prevent the energization of the switching relay during the 90 testing operation and before an idle trunk is reached. Otherwise the circuits of the two are very much the same.

What is claimed is:

1. In combination, an automatic switch, 100 trunk lines accessible to said switch, means responsive to the seizure of said switch for causing the same to hunt for an idle trunk line, and means for always advancing said switch past one of said trunk lines after it 105 is seized and before its hunting movement starts.

2. An automatic switch having a test wiper, means responsive to the seizure of 110 said switch for advancing the same independent of its test wiper, and means effective after a predetermined time for continuing the advance of the switch under control of its test wiper.

3. An automatic switch having a test 115 wiper, means responsive to the seizure of said switch for advancing the same independent of its test wiper, and delayed action means also responsive to the seizure of said switch for placing the continued advance 120 thereof under the control of its test wiper.

4. An automatic switch having a test wiper, means responsive to the taking of said 125 switch for use for advancing the same under control of its test wiper, and means effective each time the switch is used for preliminarily advancing the same independent of its test wiper.

5. An automatic switch having a test 130 wiper and a motor magnet, a circuit for said

motor magnet excluding said wiper closed when the switch is taken for use, another circuit for said motor magnet including said test wiper, and delayed action means also responsive to the taking of said switch for use for opening the first circuit and closing the second circuit.

6. An automatic switch, line and release trunk conductors terminating in said switch, means controlled over said release trunk conductor when the switch is seized to advance the switch, a test wiper, and means controlled over one of said line conductors for placing the continued advance of the switch under control of said test wiper.

7. An automatic switch, line and release trunk conductors terminating in said switch, a motor magnet controlled over said release conductor to advance the switch when the same is seized, a test wiper, and a relay energized over one of said line conductors for shifting the control of said magnet from the said release conductor to the said test wiper.

8. A line switch of the type in which the wipers normally rest on the contacts last used, and means for automatically advancing said switch whenever it is taken for use.

9. A line switch of the type in which the wipers normally rest on the contacts last used, a test wiper in said switch, means for advancing said switch independent of control by its test wiper whenever the switch is taken for use, and means for causing the advance of the switch to be continued under control of said test wiper.

10. A line switch of the type in which the wipers normally rest on the contacts last used, a test wiper and test contacts in said switch, means for advancing said switch a definite distance independent of control by said test wiper whenever the switch is taken for use, and means for causing the switch to continue its advance under control of said test wiper as long as the said wiper engages busy test contacts.

11. A line switch of the type in which the wipers rest normally on the contacts last used, a test wiper in said switch, a motor magnet for driving said switch, means for operating said motor magnet independent of said test wiper, and means for continuing the operation of said motor magnet by current flow through said test wiper and said magnet in series.

12. An automatic switch having a test wiper, means responsive to the taking of said switch for use for advancing the same under control of its test wiper, and means effective each time the switch is used for preliminarily advancing the same only one step independent of its test wiper.

13. An automatic switch having a test wiper, means responsive to the taking of said switch for use for advancing the same under control of its test wiper, and means effective

each time the switch is used for preliminarily advancing the same a plurality of steps independent of its test wiper.

14. An automatic switch having a test wiper, means responsive to the taking of said switch for use for advancing the same under control of its test wiper, and means effective each time the switch is used for preliminarily advancing the same a variable distance independent of its test wiper.

15. An automatic switch having a test wiper, means responsive to the taking of said switch for use for advancing the same under control of its test wiper, means effective each time the switch is used for preliminarily advancing the same a fixed distance independent of its test wiper, and means for readily changing the switch so that it is advanced preliminarily a variable distance.

16. An automatic switch having a test wiper, means responsive to the taking of said switch for use for advancing the same under control of its test wiper, means effective each time the switch is used for preliminarily advancing the same a fixed distance independent of its test wiper, and means for readily changing the switch so that the fixed distance is either a single step or a fixed number of steps.

17. An automatic switch having a test wiper, means responsive to the taking of said switch for use advancing the same under control of its test wiper, means effective each time the switch is used for preliminarily advancing the same only one step independent of its test wiper, and means for readily changing the switch so that it is advanced preliminarily a plurality of steps.

18. A line switch of the type in which the wipers rest normally on the contacts last used, a test wiper in said switch, a motor magnet for driving said switch, means for operating said motor magnet independent of said test wiper, and means for continuing the operation of said motor magnet by current flow through said test wiper.

19. In a hunting switch having a driving magnet operated through the test wiper of the switch during the hunting movement, a test conductor incoming to said switch, and means for placing a guarding potential on said test conductor by altering the potential supplied to said magnet.

20. In an automatic switching system, a hunting switch having a driving magnet operated through the test wiper of the switch during the hunting movement of the switch, a test conductor incoming to said switch, a plurality of similar switches, a conductor for supplying operating potential to the magnets of all said switches, and means for placing a guarding potential on the test conductors of all said switches by altering the potential on said supply conductor.

21. In combination, a line switch, a motor

magnet and a test wiper for said line switch, a relay for closing a circuit for said magnet including said wiper, a relay for energizing said first relay, and a preliminary energizing circuit for said magnet controlled by said relays jointly.

22. In combination, a line switch, a motor magnet and a test wiper for said line switch, a relay for closing a circuit for said magnet including said wiper, a relay for en-

ergizing said first relay, a preliminary energizing circuit for said magnet, contacts on the second relay for closing said preliminary energizing circuit, and contacts on said first relay for opening said preliminary energizing circuit. 15

In witness whereof, I hereunto subscribe my name this 20th day of June, A. D. 1924.

ARTHUR J. RAY.
